UNITED STATES PATENT OFFICE.

MICHAEL NICHOLSON, OF BALTIMORE, MARYLAND.

SIGNAL HEAD-LIGHT.

SPECIFICATION forming part of Letters Patent No. 225,299, dated March 9, 1880.

Application filed March 28, 1879.

To all whom it may concern:

Be it known that I, MICHAEL NICHOLSON, of Baltimore city, State of Maryland, have invented certain new and useful Improvements 5 in Signal Head-Lights; and I hereby declare the same to be fully, clearly, and exactly described as follows, reference being had to the accompanying drawings, in which the said device is illustrated, in—

10 Figure 1, in perspective view, Fig. 2 being a sectional view on line xx , Fig. 1.

My invention has reference to signal head-lights in general and to locomotive head-lights in particular.

15 It consists, broadly, in a signal-lantern having its front rim provided with colored side signals, which are adapted to be concealed, when desired, with or without a similar front signal.

20 It is customary on railroads to require a colored signal—generally a red flag by day and a red light by night—to be displayed on every engine of a convoy of trains, except the last, the object being to indicate that another 25 train is following any one which shows the red signal.

Prior to the introduction of my head-light each engine was provided with one or more 30 red lanterns in addition to the ordinary head-light, involving a considerable outlay to provide the lanterns and keep them filled and in repair.

The device about to be described furnishes 35 a head-light adapted to display colored front and side signals when desired, all being illuminated by the single light.

In the accompanying drawings, A is the 40 body of an ordinary locomotive head-light, having the usual lamp a , parabolic reflector a' , and projecting front rim, B. These parts are 45 of the usual size and shape. At either side the front rim, B, is cut away, and a projection, b , is formed thereon, extending to a point about flush with the side of the lantern. In 50 the faces of the projections b are inserted the glasses C, of appropriate color, and preferably lenticular in shape. These glasses, which 55 constitute the side signals, are inclined at about an angle of thirty degrees to the axis of the

parabolic reflector, and are so situated as to 50 receive the direct rays from the lamp a .

The side signals, C, are provided with covers c , pivoted as shown at d' , and are also provided with thimbles c' , which register with similar thimbles, d and c'' , when the cover is 55 raised or lowered, a pin, D, being passed through the thimbles and securing the cover in position.

Above the front rim is a casing, E, in which is mounted the front signal-pane, e , upon a 60 suitable shaft adapted to be revolved by means of a hand-wheel, F, in front of the casing. The pane e is inclosed in a frame, e' , and is suspended from the shaft by an arm, e'' , and is somewhat less in diameter than the radius 65 of the front opening of the lantern, so that it does not extend down to a point opposite the lamp or parabolic axis.

As a result of this construction the signal-pane does not in any material degree impair 70 or lessen the illumination of the track or tracks by the lamp and reflector.

The pane e is concealed, when desired, by revolving the wheel F until the pane is brought into the position shown in dotted lines, in 75 which position it is held by its own weight.

I make no claim here to the various minor 80 points of novelty embodied in the device described, as they are made the subjects of the claims in another application of even date here-with; and for the reason that they are therein fully set forth, I consider it unnecessary to describe here the advantages arising from the said details of construction.

What I claim is—

1. A signal head-light having its front projecting rim provided with colored signal-panes located at either side and away from the face of the lantern, and adapted to be concealed, when desired, by mechanism substantially as 90 set forth.

2. A signal head-light having lateral openings in its front rim covered by colored-glass plates, for the purpose of exhibiting side lights as signals, substantially as set forth.

3. A signal head-light adapted to exhibit front and side signals, the latter consisting of glass plates located opposite openings in the

85

95

front rim and away from the face of the lantern, as set forth.

4. A signal head-light having at either side a side signal located opposite an opening in its front flange and away from the face of the lantern, the said side signal being adapted to be concealed when desired, and inclined to

the sides of the lantern, whereby it is visible from a point dead ahead as well as from the side, as set forth.

MICHAEL NICHOLSON.
